Primary Examiner — Kevin Rudzinski*Assistant Examiner* — Kathleen Jones(74) *Attorney, Agent, or Firm* — Fay Sharpe LLP(57) **CLAIM**

The ornamental design for a tire tread, as shown and described.

DESCRIPTION

FIG. 1 is a perspective view of a full tire including the tire tread of the present application;

FIG. 2 is a partial view of the first side thereof;

FIG. 3 is a partial view of the second side thereof;

FIG. 4 is a front view thereof; and,

FIG. 5 is an enlarged partial front view thereof.

The broken lines showings of the sidewall, inner bead, and the peripheral boundary between the tire tread and the sidewall are included for the purpose of illustrating environment and form no part of the claimed design for the tire tread.

1 Claim, 5 Drawing Sheets(56)
